LOUVER CONSTRUCTION FOR VENTILATED
WINDOWS AND DOORS

Walter T. Burchill, West Los Angeles, Calif.

Application April 24, 1950, Serial No. 157,815

4 Claims. (Cl. 20—62)

1

This invention relates to windows and doors employing louver type ventilating closures. More particularly, the invention relates to a louver window of a type in which the louvers are pivoted or hinged at one edge to a fixed frame such as a window frame, and at their opposite edges are hinged to a floating frame which swings arcuately in the movement of the louvers from closed to open positions and vice versa.

The primary object of the invention is to provide an improved louver construction which is adapted particularly to the utilization of glass louvers, although it is also applicable to other types of louvers, such as wood slats.

Where glass louvers are utilized, there is the problem of mounting the ends of the louvers for pivotal movement. This requires a separate mounting member for attachment to the ends of the louvers, and for carrying the pivots by which the louvers are connected to the window frame.

One of the particular objects of the invention is to provide an improved mounting means for pivotally connecting a series of glass louvers for movement from closed positions in which they overlap each other to open positions in which they are substantially parallel and horizontal.

Another object is to provide a louver window embodying a novel and improved construction of floating frame for operating the louvers. In this respect, the invention has as one of its important objects to provide a louver construction which may be delivered to a job in a knocked-down, compactly packaged arrangement, and which can be readily assembled by a glass setter or glazier into a window opening. Another object is to provide a louver construction embodying frame elements of metal, eliminating wood construction. A further object is to provide a louver construction embodying a novel arrangement for yieldingly supporting a floating louver frame in a normally raised, closed position, with the weight of the frame substantially balancing the yielding means so that it may be positioned in any selected position of adjustment between the closed and open positions. A further object is to provide an improved combination of floating frame and locking member for locking the floating frame against opening movements beyond the selected position. A further object is to provide an improved arrangement for mounting the lowermost louver to shift to an inclined, moisture draining position on the window sill when the louvers are in their fully open positions.

A further object is to provide an improved

2

louver construction which is readily adaptable to all sizes of window openings, and is not restricted to sizes constituting multiples of the width of the louvers.

5 A further object is to provide a louver construction capable of being readily mounted in a framed window opening and adjusted to plumb, level, and accurately rectangular positions in the window opening even though the opening may be slightly irregular. This is particularly important in a louver window having many pivotal connections which would tend to bind under even slight mis-alignment conditions.

Other objects will become apparent in the ensuing specification and appended drawings in which:

Fig. 1 is an inside elevational view of a louver window embodying my invention, shown in approximately a half-open position, with all parts thereof shown in their relative positions as installed in a rough framed opening in a building but with the rough framing omitted in order to illustrate the metal frame members of my window;

25 Fig. 2 is a fragmentary vertical sectional view thereof taken on the line 2—2 of Fig. 1;

Fig. 3 is a fragmentary vertical sectional view thereof taken on the line 3—3 of Fig. 1;

30 Fig. 4 is a fragmentary elevational view of the inside of the window, on a larger scale than Fig. 1;

Fig. 5 is a detail perspective view of one of the louver mounting clips;

Fig. 6 is a detail sectional view taken on the line 6—6 of Fig. 1;

35 Fig. 7 is a detail horizontal sectional view taken on the line 7—7 of Fig. 3; and

Fig. 8 is a detail sectional view of a modified form of the lost motion connection between the lowermost louver and the floating frame.

40 Referring now to the drawings in detail, and in particular to Fig. 1 (which views the inner side of the window, with the window about half open), I have shown as one example of one form in which the invention may be embodied, a louver window mounted in a rough framed window opening defined by side frame members 10, a top frame member 11 and a sill member 12. It will be understood that these frame members are part of the framing of the building in which the window is installed and form no part of the present invention, except insofar as the sill member 12 cooperates with the lowermost louver as will be specified more in detail hereinafter.

45 The louver construction of my invention includes members collectively constituting a fixed

frame which is indicated generally at 13, against which a floating frame, indicated generally at 17, is adapted to establish sealing contact in a closed position thereof. In the ensuing description and claims, the movement of said floating frame 17 toward said closed position will be referred to as a "forward" movement, and the movement of the floating frame toward its open position will be referred to as a "rearward" movement; also, certain parts of the respective frames will be referred to as projecting in such forward and rearward directions. The terms "inner" and "outer" will be used hereinafter as meaning toward the center of the window and away from the center of the window respectively. The apparatus of the invention further includes a series of louvers 14 each having its lower, forward edge hinged by a hinge 15 to the fixed frame 13, and each having its upper, rearward edge hinged by hinges 16 to the floating frame. The fixed frame 13 is attached to the forward side of the rough frame 10—12, which forward side is at the right of Figs. 2 and 3.

Referring now to Fig. 2, the floating frame 17 is adapted to move from the closed position, shown in full lines, to any one of a series of partially open positions or a fully open position, shown in dotted lines in that figure. In the closed position, the floating frame is at a maximum elevation with its upper extremity seated against the upper member 18 of fixed frame 13 and its lower extremity spaced above the sill member 12. In its fully open position, its lower member is seated against the sill 12 and its upper member is spaced downwardly and rearwardly from the upper fixed frame member 18, all as indicated in the dotted line showing. In the closed position, the louvers 14 have their adjacent marginal portions overlapped and in face to face sealing engagement with each other as shown best in Fig. 3, the upper marginal portions of the respective louvers being disposed rearwardly of the lower marginal portions of the adjacent louvers.

The fixed frame 13 is of metal section, preferably of extruded aluminum or aluminum alloy. It includes a top member 18, side members 19 and a bottom member 20. The top and side members 18 and 19 each include a web portion 21, a flange 22 branching rearwardly from web member 21, a flange 23 branching forwardly from web 21 and offset toward the center of the window from flange 22, a flange 24 forming a continuation of web 21 outwardly of flange 22, and a flange 25 forming a continuation of web 21 inwardly of flange 23. In addition, side members 19 include a flange 26 branching rearwardly from flange 25. The bottom frame member 20 is of Z-bar construction including a top flange 22' to rest upon the sill 12 at the forward margin thereof, a web member 21' and a bottom flange 23'. Flanges 23 and 23' cooperatively define an opening to receive a screen or storm sash. Flanges 22, 22' fit against the inner faces of the rough frame members 10, 11, 12 respectively, whereby to mount the fixed frame in the rough frame. In the event of any irregularity in shape, in angularity of the corners, or in leveling of the rough frame members, it is possible to adjust the fixed frame 13 to a level, plumb condition in which it defines an accurately rectangular opening, simply by inserting shims or the like between selected extremities of the frame members 18, 19, 20 and the rough frame members 10, 11, 12 respectively. In the installation of the window, the fixed frame members 18, 19, 20 will be packaged and shipped in

knock-down condition and will be assembled and secured to the rough frame members 10, 11, 12 by means of screws 27. Suitable apertures are provided in flanges 22 and 24 and in flanges 22' and web 20 so that screws 27 may be inserted both vertically and horizontally through all of these flanges. The flanges 22 and 22', and the web member 21 cooperatively define a frame to receive the floating frame 17.

10 Floating frame 17 comprises upper and lower corner elbow fittings 28 and 29 respectively, an upper cross member 30, a lower cross member 31, and side rails 32. Members 30, 31 and 32 are of tubular, extruded metal (preferably aluminum) construction. Member 30, as shown in Fig. 3, is of tubular cross section, having a slot in its lower side. Lower cross member 31, is, in cross section, an arcuate segment of a tube. Side members 32 (Figs. 6 and 7) have a cross sectional shape generally in the form of a letter G, rounded on one side as at 33 and squared at the other side to provide a flange 34, which, in the assembled window, is disposed in the same plane as flange 26 and opposed thereto. The side from which flange 34 projects is extended beyond flange 34 to define a flange 35 which is opposed to and parallel to flange 25 of the fixed frame. At this point it may be noted that flanges 26, 34, 25 and 35 cooperatively define, in the closed position of the floating frame, a channel to receive the end extremities of louvers 14. Flange 26 provides a support to which hinges 15 are connected, and flange 34 provides a support to which hinges 16 are connected. Thus the louvers are hinged at their lower margins to the fixed frame flanges 26 and at their upper margins to the floating frame flanges 34.

25 The louvers 14 will ordinarily be of plate glass construction, whereby the window will be transparent when the louvers are closed. In order to provide hinged connections between the glass louvers and the respective frame members, the invention provides a sheet metal clip which is shown in Fig. 5 and referred to generally by the reference numeral 43. This clip is generally of channel shape, including a web member 36 and side flanges 37 each of which terminates in a rolled hinge loop 38. The ends of the glass louvers are received in these channels, and embraced by the side flanges 37. Flanges 37 are cut away as shown to allow the louvers to make direct contact with each other in their overlapping marginal portions. In the hinge loops 38 are mounted hinge pins 39 which are pivotally received in openings suitably positioned in the respective flanges 26 and 34. The ends of web 36 are bent to form tabs 46 which embrace the respective edges of the panel 14 to retain the panel against displacement in the clips.

30 Elbow fittings 28 and 29 include corner portions of cylindrical shape corresponding in diameter to the frame members 30, 31 and 32, so as to form flush continuations thereof, and include reduced diameter shank members 40 which project beyond the corner portions and are received respectively in the ends of frame members 30—32. The diameter of shanks 40 is such as to snugly fit within the tubular upper frame member 30 and also to fit the rounded parts of side frame members 32 as indicated in Fig. 7. Disposed in the central plane of each elbow fitting, and extending throughout the corner portions and extended shanks thereof, are grooves 41 which are of the same width as the slot in the bottom of top frame member 30. The grooves 41

function, in the upper portion of the floating frame, to receive a fixed panel 42. They have a different function in the lower part of the folding frame as will shortly be pointed out.

One of the important aspects of the invention is the utilization of a fixed panel 42 in the top of the floating frame, to close any gap that may exist between the upper margin of the uppermost louver 14 and the top member 30 of the floating frame. Thus the invention provides for utilizing a standard width louver and a single standard mounting clip, and at the same time adapts the windows to any height opening that may be encountered, the adjustment being made in the width of the fixed panel 42.

The panel 42 which will ordinarily be thinner than the breadth of grooves 41, in which event it may be sealed therein, and in the slot in frame member 30, by means of a strip 44 of any suitable sealing material such as felt, rubber, plastic composition, or the like. The width of panel 42 will in each case be determined by the variation of the total height of the window opening from the standard height which would bring the vertical inside dimension of the floating frame to a multiple of the net width of louvers 14.

One of the important aspects of the invention is an improved mounting for the lowermost louver 14 which provides for arresting the downward hinging movement thereof at the inclined position indicated in dotted lines at the bottom of Fig. 3, while the remaining louvers continue to swing downwardly until they reach the horizontal positions indicated in dotted lines in Fig. 2. To this end, the invention provides an improved lost motion connection between the lowermost hinges 16 and the floating frame 17. This lost motion connection is provided in the form of floating hinge blocks 45 which may, as indicated in Fig. 3, be of bar shape, fitting fairly snugly within grooves 41 in lowermost corner fittings 28, but freely slidably therein. The lowermost hinges 16 may comprise rigid, permanent connections between pins 39 and the lower inner corners of slidable hinge fittings 45 of bar shape, with these pins 39 pivotally received in loops 38 at the upper corners of the lowermost louver 14. The upper portions of hinge fittings 45 are confined by the lower portions of flanges 34, as indicated in Figs. 3 and 7 (flanges 34 being partially broken away in Fig. 7 to better illustrate the hinge pins 39).

It will now be apparent that as the bottom of floating frame 17 approaches the sill 12, lowermost louver 14 will be arrested by contact with the shoulder 43 of the upwardly and inwardly inclined upper surface of sill 12. Inwardly of shoulder 43, sill 12 is cut away to provide a recess 49 to receive lower frame member 31 of the floating frame. After lowermost louver 14 has been arrested by shoulder 43, the louver frame will continue to move downwardly until lower frame member 31 rests against sill 12 in recess 39, the hinge fittings 45 sliding upwardly in grooves 41 to provide the necessary lost motion between the lowermost hinges 16 and the floating frame, to allow the latter to move on downwardly into contact with sill 12. The relative positions of lowermost hinges relative to lower frame members 31 are indicated in the full line and dotted line positions respectively in Fig. 3.

In Fig. 8 is shown a modified form of the lost motion hinge fitting, which may be employed in an arrangement in which the relative thicknesses of louvers and floating frame may be such as to

permit of the hinges 16 being centered with reference to the plane of grooves 41. In this case, lost motion hinge fittings 45a may be in the simple form of rollers of diameter and thickness corresponding to the width and thickness of hinge fitting bars 45. By abutting engagement with clips 43, rollers 45 will be confined against any possible escape from grooves 41. Their movement in grooves 41 may be partially a rolling one, thereby reducing friction.

The invention provides an improved arrangement for yieldingly counterbalancing a majority (but not all) of the weight of the floating frame and louvers. Such counterbalancing means is in the form of a pair of compression coil springs 50 received within the respective side members 33 of the floating frame and engaged under compression between the lower extremities of corner fittings 28 (shanks 40 thereof) and necked washers 51, which are suspended upon cables 52 the upper ends of which are anchored to upper rough frame member 11 in any suitable manner as, for example, by means of screweyes 53 extending through flanges 22 and threaded into frame member 11. The lower ends of cables 51 are headed as at 54 to engage washers 51. Cables 51 extend through openings in the upper sides of corner fittings 28 as indicated in Fig. 2. As the floating frame 17 is swung downwardly, cables 51 will be drawn out through these openings and shifted to positions inclined downwardly and rearwardly as indicated in dotted lines in Fig. 2. Coil springs 50 will be correspondingly compressed. When the window is returned toward the closed position, springs 50 will carry the majority of the load, and only a slight amount of lifting pressure will be required.

The weight of the floating frame and louvers may be slightly greater than, or slightly less than, the spring loading, but in any case is substantially the same, sufficiently so that the friction in the moving parts will be greater than any excess of weight over spring loading or vice versa, whereby some effort will be required to move the window in either the opening or the closing direction, although relatively slight effort is required in either case. In any event, there is a sufficient balance between weight and spring loading and frictional resistance to movement in either direction, so that the window may be readily moved in either direction and yet will stay in any adjusted position as the result of frictional resistance combined with the balancing of loads.

However, in order to provide additional assurance of preventing the window from moving toward open positions beyond a selected position of adjustment, the invention provides one or more latch bolts 55, preferably of square section metal rod, slidably mounted in grooves 41 between the bottoms of the grooves and hinge fittings 45. Each bolt 55 is provided with a handle 56 pivotally connected to its upper end and operable in a slot 57 extending vertically in side frame member 32. Slot 57 has a plurality of notches 58, suitably slanted downwardly and inwardly to receive and hold handle 56 to latch the bolt 55 to the floating frame in any one of several positions of adjustment, such as that indicated in dotted lines in Fig. 2. With its lower end engaged against sill 12 and its upper end latched to the floating frame by engagement of handle 56 in the notch 58, latch bolt 55 will support the frame against downward movement beyond the selected position of adjustment. Such locking of the window against downward move-

ment may be utilized to secure it from being blown open by a strong wind acting against the outer faces of louvers 14. In the absence of such conditions, it may not be necessary to utilize the bolts 55.

The floating frame may be provided with a pair of handles 59 attached to side members 32, for manual operation of the window.

I claim:

1. In a louver window embodying a fixed frame and a floating frame and a plurality of louvers each hinged at its upper margin to the floating frame and at its lower margin to the fixed frame, for downward and rearward opening movement; said fixed frame comprising a series of frame members including side members of extruded metal section each embodying a main web portion and outer and inner flanges extending rearwardly therefrom to define a channel section, a flange extending inwardly from channel section and cooperating with the inner of said rearwardly extending flanges to define an inner angle section; and said floating frame comprising a series of members including side members of extruded metal section of a cross sectional shape resembling the letter G each embodying an outer semi-tubular portion and an inner angle section including flanges extending respectively forwardly and inwardly, said semi-tubular outer portion having a forward extremity adapted to enter said channel section of the corresponding fixed frame member and to seat against the web portion of the latter to seal the window in the closed position thereof, the respective angle sections of said fixed frame and floating frame members being adapted to cooperate in the closed position of the window, with the respective forwardly and rearwardly extending flanges thereof in substantially abutting engagement, to define an inwardly opening channel in which the end portions of said louvers are received; and hinge means connecting said end portions, at the respective upper and lower margins of said louvers, to the respective rearwardly and forwardly extending flanges of said angle sections.

2. A window as defined in claim 1, wherein said fixed frame side members each include outer flanges extending outwardly from and constituting continuations of said web portions, and cooperating with the outer, rearwardly extending flanges thereof to define outer angle sections adapted to receive the forward corner portions of building framing members for attaching the fixed frame thereto.

3. In a louver window embodying a fixed frame and a plurality of louvers each hinged at its upper margin to the floating frame and at its lower margin to the fixed frame, for downward and rearward opening movement from a raised, closed position; said fixed frame comprising a series of frame members including side members of extruded metal section each embodying a main web portion and outer and inner flanges extending rearwardly therefrom to define a channel section, and a side flange extending inwardly from said channel section as a continuation of said web portion and cooperating with the inner of said rearwardly extending flanges to define an inner angle section; and said floating frame comprising a series of members including side members of extruded metal section each embodying an outer semi-tubular portion and an inner angle section including flanges extending respectively forwardly and inwardly, said semi-tubular outer portion having a forwardly extending

part adapted to enter said channel section of the corresponding fixed frame member so as to seal the window in the raised, closed position of said floating frame; said floating frame member cooperating with said associated fixed frame member in said raised, closed position, to define a tubular enclosure for a balancing spring, said angle section of the floating frame member, in said raised, closed position thereof, being opposed to said angle section of the fixed frame member, with the respective forwardly and rearwardly extending inner flanges disposed in a common plane and in edge-to-edge opposition to define an inwardly opening channel in which the ends of said louvers are received; and means pivotally connecting the ends of said louvers at the respective upper and lower margins of said louvers, to said respective rearwardly and forwardly extending inner flanges.

4. In a louver window embodying a fixed frame and a plurality of louvers each hinged at its upper margin to the floating frame and at its lower margin to the fixed frame, for downward and rearward opening movement from a raised, closed position; said fixed frame comprising a series of frame members including side members of extruded metal section each embodying a main web portion and outer and inner flanges extending rearwardly therefrom to define a channel section, and a side flange extending inwardly from said channel section as a continuation of said web portion and cooperating with the inner of said rearwardly extending flanges to define an inner angle section; and said floating frame comprising a series of members including side members of extruded metal section each embodying an outer semi-tubular portion and an inner angle section including flanges extending respectively forwardly and inwardly, said semi-tubular outer portion having a forwardly extending part cooperating with said channel section of the corresponding fixed frame member so as to seal the window in the raised, closed position of said floating frame; said floating frame member cooperating with said associated fixed frame member in said raised, closed position, to define a tubular enclosure for a balancing spring, said angle section of the floating frame member, in said raised, closed position thereof, being opposed to said angle section of the fixed frame member, with the respective forwardly and rearwardly extending inner flanges disposed in a common plane and in edge-to-edge opposition to define an inwardly opening channel in which the ends of said louvers are received; and means pivotally connecting the ends of said louvers at the respective upper and lower margins of said louvers, to said respective rearwardly and forwardly extending inner flanges.
